BOXED PRODUCE HANDLING EQUIPMENT

Harry C. Brest, Pomona, Calif., assignor to R. M. Walcott Co., Pomona, Calif., a copartnership

Application November 25, 1946, Serial No. 712,222

9 Claims. (Cl. 214—89)

1

This invention relates to an apparatus for receiving and conveying produce, and is particularly adapted for installation in a packing house where produce is received at one level to be taken to a lower level and automatically conveyed to a remote point for storing or packing.

A major object of the invention is to provide packing house equipment that is capable of lowering stacks of produce-filled boxes from the receiving level to a lower level, and operable to automatically convey the box stacks from the lowering apparatus to a remote location for further disposition. From a standpoint of practical operation, the invention is of particular advantage with respect to minimizing any manual handling of the produce in that the boxes may be trucked off of the delivery car onto the lowering platform in a stacked formation, automatically taken to a lower level, and transferred to a conveyor to be carried to a remote location as where the stack is to be trucked from the conveyor to its storage space.

Particularly contemplated is the use of a pair of lowering carriers or platforms movable vertically but in opposite relation so that one is in counterbalancing relation to the other. A particular object of the invention is to accomplish automatic transfer of the box stack from the carriers to a receiving station, specifically by a transfer mechanism responsive automatically to the arrival of the carriers at their lower positions.

A further object of the invention is to provide for the automatic transfer of the box stack from the dual carriers to a single or common receiving station from which the box stacks are conveyed automatically for disposal at a remote location. In this connection the invention particularly contemplates the use of a vertically movable platform as the single receiving station, by which the box stacks or individual box loads may be lowered and deposited on the traveling conveyor, all in predetermined timed relation to the operation of the lowering carriers.

The invention contemplates various additional features and objects, including the specific details of the carrier operating mechanisms, the receiving station and conveyor, and various manual and automatic controls for assuring the operation of the various mechanism in the intended sequence. All these, however, as well as the general features referred to, will be understood from the following detailed description of a typical embodiment of the invention, throughout which reference is had to the accompanying drawings, in which:

2

Fig. 1 is a side elevation of the apparatus showing a typical embodiment of the invention;

Fig. 2 is an enlarged fragmentary horizontal section taken on line 2—2 of Fig. 1;

Fig. 3 is a fragmentary vertical section taken substantially as indicated by line 3—3 of Fig. 2, showing certain parts in side elevation;

Fig. 4 is an enlarged fragmentary vertical section taken on line 4—4 of Fig. 1;

Fig. 5 is a diagrammatic view illustrating the hydraulic system embodied in the apparatus; and

Fig. 6 is a diagrammatic illustration of the drive and the electrical circuits for controlling operation of the drive.

15 The apparatus as illustrated in the drawings is adapted for lowering produce from a receiving level 11 to a storage level 12 and automatically conveying the produce to a point remote from the lowering apparatus. The lowering apparatus includes generally a pair of platforms 13 and 14 operating in spaced vertical shafts 15 and 16 and carried on the upper end of plungers 17 and 18 operating in stationary cylinders 19 and 20. The cylinders and their controls are located in 25 a pit 21 below the storage level 12.

The lowering platforms 13 and 14 travel vertically between the receiving level 11 and the storage level 12 alternately and in opposite directions relative to one another under the control of a hydraulic system 25 interconnecting the cylinders 19 and 20 and operated through gravity by the weight of the produce loaded alternately on the platforms at the receiving level. The cylinders rest on the bottom 22 of the pit 21 and are provided with packing glands 23 and 24 at their upper ends surrounding the plungers 17 and 18 for sealing the fluid in the cylinders.

The hydraulic system 25 interconnecting the cylinders controls the flow of fluid from one cylinder to the other, and includes generally a pair of interconnecting lines 26 and 27 each controlling the flow of fluid in one direction only. The line 26 permits the flow of fluid from the cylinder 19 to the cylinder 20 while line 27 permits the flow of fluid from cylinder 20 to cylinder 19. Flow in opposite directions is prevented by check valves 28 and 29. Lines 26 and 27 are provided with valves 30 and 31 controlling the flow of fluid through said lines and manually operable by handles 32 and 33 located above the receiving level 11.

Separate controls 34 and 35, connecting the operating handles 32 and 33 with their respective valves 30 and 31, are identical in construction and operation and may each include a

vertically reciprocable bar 36 carrying the handles 32 and 33, accessible at the outside of the front plate 37 of the shaft 15 and 16. The lower end of each bar 36 is pivotally connected with a link 38 connecting with one end of a double ended lever 39 pivoted at 40 to a bracket 41 located below the receiving level 11. The other end of each lever 39 is connected with a vertical rod 42 extending below the storage level 12 and connected with a lever 43 carried on control shafts 44. Each control shaft 44 is rotatably carried by a supporting frame member 45, extending between and secured to the cylinders 19 and 20 and carrying fixed lever 46 connected through link 48 with the control valve lever 47. Thus reciprocation of either control bar 36 by its operating handle 32 or 33 will cause operation of its control valve 30 or 31 to permit flow through its respective line 26 or 27 interconnecting the cylinders 19 and 20. The interconnecting lines 26 and 27 may be provided with suitably located valves 49 for isolating sections of the lines in the event of repair or replacement of the valves 30 or 31 and may also be manually adjusted to regulate the flow through the lines.

The lowering platforms 13 and 14 may be identical in construction and may each include a series of rollers 51 arranged in a horizontal plane and carried by spaced side plates 52 supported on a base plate 53 secured to the upper end of their respective plungers 17 and 18 by a mounting flange 54. The platforms 13 and 14 are guided for vertical reciprocation in their respective shafts 15 and 16 by pairs of angle irons 55 located at opposite sides and the outer end of each platform. Guide lugs 56 carried by the side plates 52 and the outer end of each platform cooperate with the pairs of guides 55 during their reciprocal movement.

Power driven conveying means 57 is provided in conjunction with the lowering platforms for automatically removing the stacks S of produce filled boxes from the platforms upon descent of a platform to the plane of the storage level 12. The power driven conveying means includes a pair of spaced drive rollers 58 for cooperating with the outer pairs of each set of rollers 51 of the respective platforms 13 and 14.

Setting controls 60 and 61, provided in the hydraulic system 25 interconnecting the cylinders 19 and 20, include relief valves 62 in the by-pass lines 26a, 27a and operable by engagement of the platforms 13 and 14 with plungers 63 carried for vertical reciprocation in guide tubes 64 mounted on the frame structure F, see Fig. 4. The lower ends of the rods 63 are connected with their respective valve arms 65. Upon approaching the storage level 12, a platform will engage its respective plunger 63 and cause opening of its relief valve 62 to permit a restricted flow of fluid through the by-pass line 26a or 27a and simultaneous closing of its control valve 30 or 31 through a similar plunger means 66. The latter includes spaced plungers 67 located adjacent the plungers 63 and operable by engagement with the platform to cause closing of their respective control valves. Plungers 67 are carried for reciprocation by guide tubes 68 mounted on the frame work F and have their lower ends connected with lever arms 69 fixed to the control shafts 44 through connecting links 70.

It will be seen how engagement of a platform with a pair of plungers 63, 67 will cause simultaneous

opening of a relief valve 62 and closing of a control valve 30 or 31 to permit a restricted flow of fluid from one cylinder to the other and consequent retarding of the lowering speed of the platform as the platform settles onto the drive rollers 58. Engagement of the outer pairs 51 of the platform rollers with the drive rollers 58 will convey the stack S of boxes off of the platform, as will be later described.

10 A transfer table or platform 71 located centrally between the platforms 13 and 14 and at the storage level 12, is adapted to alternately receive a stack S of boxes from the platforms. The transfer platform includes spaced side plates 15 72 for rotatably carrying a series of rollers 73 and supported on a base plate 74 secured to the upper end of a plunger 75 through a mounting flange 76. The plunger 75 is reciprocable in a stationary cylinder 77 carried at its upper end by the frame work F and at its lower end by the supporting member 45.

15 Means 78 for lifting the transfer platform 71 includes hydraulic pumps 79 at opposite sides of the cylinder 77 and located between each set of plungers 63 and 67 for engagement by the platforms 13 and 14 upon their descent. The lower end of each pump 79 is connected with the cylinder 77 by a valved line 80 for controlling the communication between the pump and the cylinder. The operation of the pumps 79 will be subsequently described.

20 An interconnecting mechanism 81 is provided in conjunction with the transfer platform and controls 34 and 35 for the valves 30 and 31, to control operation of the drive rollers 58, stopping of the drive rollers and lowering of the transfer table 71. The mechanism 81 includes a plate 82 supported by the frame F for lateral reciprocation and in line with the vertical plane of the spaced plungers 79a of the pumps 79. The center of the control plate 82 is provided with an elongated opening 83 for passing the plunger 75 of the transfer platform, and the opposite ends of the plate are adapted to alternately engage flanges 84 of the plungers 79a. The control further includes a double-ended yoke 85 pivoted intermediate its ends at 86 to the frame F and a double ended lever 87 pivotally connected at 88 to its opposite ends. Levers 87 are provided at one end with pin and slot connections 89 with the control plate 82. The other ends of the levers 87 are provided with box engaging plates 90 to be alternately engageable by a stack of boxes moving in opposite directions from the platforms 13 and 14.

25 With the apparatus in the position illustrated throughout the drawings, the platform 13 has made its descent, the outer pairs of rollers 51 are in engagement with the spaced drive rollers 58, and the platform body has closed switch 91, see Fig. 6, in series with a second switch 92 previously closed by a projection 93 on the underside of the control plate 82. The series connected switches 91, 92 are connected with one side of a reversing switch 94 in the power supply 95 to the motor 96 for controlling operation of the drive rollers 58. Closing of switches 91 and 92 will cause reversing switch 94 to energize motor 96 and drive rollers 58, through the diagrammatically illustrated drive shown by the dotted lines 97 of Fig. 6, and cause rotation of rollers 51 of the platform 13 and the rollers 73 of the transfer platform 71. Rotation of the rollers causes the stack S of boxes to shift from the platform 13 onto the platform 71. Engagement of the stack

S with the box engaging plate 90 of lever 87, located in the path of the stack S, shifts the control plate 82 and moves lug 93 out of engagement with the contactor of switch 92, with consequent de-energization of the drive motor 96. Shifting of plate 82 causes one end of the plate to lock plunger 79a in its down position under the platform 13, and its other end simultaneously to release plunger 79a under platform 14. Release of the plunger 79a located under the elevated platform 14 allows the plunger to raise and permit the transfer platform 71 to settle.

A continuously driven spaced chain conveyor 100 runs at right angles to the direction of movement of the stack S from the platforms 13 and 14 onto the transfer platform. One chain of the conveyor is located between the opposing ends of the platforms 13 and 71, and the other chain, between platforms 14 and 71, with the upper surface of the chains slightly above the plane of the storage level 12 and below the plane of the stack of boxes moving from the lowering platform onto the transfer platform. The spaced chains 100 extend to remote points at opposite sides of the transfer platform and are carried by spaced sprockets 101, as diagrammatically illustrated in Fig. 6. The chains 100 are live chains driven by a motor 102 under the control of a manual reversing switch 103 for governing the direction of rotation or travel of the chains. The chains may be guided and supported in channels 104 with their upper surface parallel to the storage level 12 and slightly above, to give the traveling stacks of boxes suitable clearance from the floor of the storage level 12.

In considering the operation of the apparatus, starting with the parts in the condition illustrated throughout the drawings, assume the lowering platform 13 with the stack S of loaded boxes has made its descent, bringing the rollers 51 of the platform into engagement with the drive rollers 58 and causing switch 91 to close, completing the circuit to the drive motor 96. Energization of the motor starts the stack S of boxes traveling onto the transfer platform 71, and brings the forward edge of the stack S against the control lever 87 with resultant shifting of the control plate 82 and opening of switch 92. Thus the drive motor is de-energized and plunger 79a released to allow the transfer platform to settle. In this manner the transfer platform sets the stack of boxes on the live conveyor chains 100 which, depending upon the direction of rotation of the drive motor 102, carries the boxes in one direction or the other. Shifting of the control plate 82 causes simultaneous shifting of the other control lever 87, at the opposite side of the transfer platform 71, to move its shoulder 87a out from under the exposed intermediate shaft portion 51a of the innermost roller on the lowering platform 13. Simultaneously with the opening of switch 92 a second lug 93 at the opposite end of the control plate 82 engages a second switch 92 to close the switch and set up a second circuit for the reversing switch 94, to be later described.

The stack S of boxes carried laterally on the chains 100 is required to travel a given distance before the next lowering platform 14 can be released, to assure clearance of the stack from the transfer platform 71 and prevent the transfer platform from dumping the stack upon its subsequent upward travel to position for receiving the next stack of boxes. Locking means 105 is provided in the manual controls 34 and 35 to prevent release of a loaded platform until the previous

stack S has cleared the transfer table. Such locking means may include a pair of latch plates 106 pivotally mounted at 107 to the frame structure F in the horizontal plane of the control plate 82. The latch plates 106 cooperate with notches 108 in the valve control plungers 67 when the plungers are down and their control valves 30 or 31 are closed. Cam projections 109 carried on the opposite ends of the control plate 82 engage arms 110 on the latch plates 106 to alternately pivot the latch plate into the notch 108 as the control plate 82 is reciprocated, see Figs. 2 and 4. Engagement of plate 106 with a notch 108 in the control plunger under platform 14, prevents movement of the manual control 35 and opening of its valve 31. To release the manual control 35 for operation, the stack S of boxes is required to move onto the transfer platform 71, and in so doing to shift the control plate 82 to move cam projection 109 out of engagement with the arm 110. Release of the control plate 82 from the plungers 79a permits settling of the transfer table 71.

The forward side of the lower box in the stack 25 S moving on the chains 100, is brought into engagement with a roller 111, carried on a bell crank 112 and pivotally mounted at 113 to the frame structure F. The bell crank 112 is connected to the plunger of a hydraulic pump 114 mounted on the frame structure F. Contact of the stack of boxes with the roller 111 swings the bell crank to operate the pump 114, causing a flow of fluid through line 115 from the pump cylinder to a pair of pumper cylinders 116 located adjacent the end of each latch plate 106 and adapted to release a latch plate from its notches 108 depending upon which latch plate has been released. A relief valve 118 is provided in a by-pass line 119 extending from the line 115 to a reservoir 120. The operating arm 121 of the relief valve is connected with an extension 122 of the bell crank 112 by a link 123, to cause the relief valve to open, after the pump has been given an initial stroke sufficient to operate the bumper cylinder plungers 117, allowing return of the spring loaded plungers 117 and by-pass of the fluid through line 115 and 119 to the reservoir 120. As the stack of boxes passes the roller 111 on the bell crank 112, the latter and its associated parts 50 will return to their normal positions and the pump is recharged through the non-return line 124 connected with the reservoir 120.

Where the chains 100 are adapted to selectively travel in either direction transversely from the transfer table 71, a double control is provided for the bumper cylinders 116 at opposite sides of the transfer table as indicated in Fig. 4 of the drawings.

After the stack S of boxes from the platform 60 13 has passed the roller 111 of the control just described and the bumper cylinder 116 has released the latch plate 106 governing the manual control 35 for valve 31, the operator may release the platform 14 for its descent. Upon approaching the storage level 12, the platform will engage its plunger 63, causing relief valve 62 in line 27a to open, and engage plunger 67 to cause control valve 31 to close, allowing a restricted flow through by-pass line 27a and a gradual settling of 70 the platform onto the drive rollers 58. During the settling of platform 14, the center exposed portion of shaft 51a of the innermost roller 51 engages notch 87a, causing downward movement of the control lever 87 and pivoting of the yoke 85, 75 with resulting upward movement of the other

control lever 87 at the opposite side of the transfer platform 71. Lever 87 under the platform 14 is then out of the way of its stack of boxes and the other control lever 87 at the opposite side of the transfer platform is in position to be engaged by the stack of boxes moving onto the platform 71.

Coming to rest on the drive rollers 53, platform 14 closes switch 91 connected in series with previously closed switch 92 (closed by the control plate 82) to cause operation of the reversing switch 94, energization of the drive motor 96 and movement of the stack of boxes off of the platform 14 onto the platform 71. Engagement of the stack of boxes with the control lever 87 shifts the control plate 82 back to the position illustrated throughout the drawings, and opens switch 92 to the reversing switch 94 to de-energize the drive motor 96. Simultaneously the latch plate 82 releases plunger 79a located at the other side of the platform 71, allowing the platform to settle and the stack to be picked up by the live chains 100 and conveyed to a remote point. Shifting of plate 82 also conditions latch 106 under platform 13 for release by its bumper cylinder 116 and causes cam projection 109, located at the other end of the plate, to move latch 106 into notch 108 of its control plunger 67.

A pair of limit switches 125 are positioned at the extreme ends of the chain conveyor 100 for engagement by a stack of boxes. These switches are in series in the main supply line 95 to control the supply to the motors 96 and 102, as diagrammatically illustrated in Fig. 6, and are adapted to stop both motors in the event a stack of boxes should reach the end of the conveyor.

To compensate for fluid loss from either cylinder 19, 20 or 77, I provide a suitable hand operated replenishing pump 130 and reservoir 131, see Fig. 5. Line 132 extending from the reservoir to the pump is provided with a non-return check valve 133. Common line 135 extending from the pump 130 is provided with a non-return check valve 136. Branch lines 137, 138 and 139 extend from line 136 to the cylinders 19, 20 and 77, respectively, and are each provided with a manual valve 140. When a selected valve 140 is opened and the pump 130 is manually operated, a replenishing supply of fluid will be delivered to the selected cylinder. To permit the cylinders to be drained or bled, I provide return lines 141, 142, and 143 to the reservoir from the branch lines 137, 138 and 139. Each line 141, 142, 143 has manual valve 144 for selectively controlling the return of fluid from any one of the cylinders 19, 20 or 77.

I claim:

1. Apparatus for receiving and conveying box stacks, comprising a pair of carriers, means associating the carriers for alternate vertical travel so that one carrier is positioned to receive a box stack at an upper station while the other carrier is at a lower station, a stack conveyor, means operable to shift the box stack transversely from the carrier at said lower station, a movable transfer means for taking the stack discharged from the carrier and depositing it onto said conveyor, and means operable by movement of the carriers for positioning the transfer means to receive the discharged stack.

2. Apparatus for receiving and conveying box stacks, comprising a pair of carriers, means associating the carriers for alternate vertical travel so that one carrier is positioned to receive a box stack at an upper station while the other carrier

is at a lower station, a stack conveyor, means operable to shift the box stack transversely from the carrier at said lower station, a movable transfer means for taking the stack discharged from the carrier and depositing it onto said conveyor, and means operable by movement of the stack discharging from the carrier to condition said transfer means for movement.

3. Apparatus for receiving and conveying box stacks, comprising a pair of carriers, means associating the carriers for alternate vertical travel so that one carrier is positioned to receive a box stack at an upper station while the other carrier is at a lower station, a stack conveyor, means operable automatically and by virtue of the arrival of a carrier at said lower station to shift the box stack transversely from the carrier, and a movable transfer means for taking the stack discharged from the carrier and depositing it onto said conveyor.

4. Apparatus for receiving and conveying box stacks, comprising a pair of carriers, means associating the carriers for alternate vertical travel so that one carrier is positioned to receive a box stack at an upper station while the other carrier is at a lower station, a stack conveyor, means operable automatically and by virtue of the arrival of a carrier at said lower station to shift the box stack transversely from the carrier, a movable transfer means for taking the stack discharged from the carrier and depositing it onto said conveyor, and means operable by movement of the carriers for positioning the transfer means to receive the discharged stack.

5. Apparatus for receiving and conveying box stacks, comprising a pair of carriers, means associating the carriers for alternate vertical travel so that one carrier is positioned to receive a box stack at an upper station while the other carrier is at a lower station, a stack conveyor, means operable automatically and by virtue of the arrival of a carrier at said lower station to shift the box stack transversely from the carrier, a movable transfer means for taking the stack discharged from the carrier and depositing it onto said conveyor, and means operable by movement of the stack discharging from the carrier to condition said transfer means for movement.

6. Apparatus for receiving and conveying box stacks, comprising a pair of carriers, means associating the carriers for alternate vertical travel so that one carrier is positioned to receive a box stack at an upper station while the other carrier is at a lower station, a manual control for governing travel of the carriers, a stack conveyor, means operable to shift the box stack transversely from the carrier at said lower station, a movable transfer means for taking the stack discharged from the carrier and depositing it onto said conveyor, and means for normally holding said manual means inoperative and conditioned by movement of the box stack.

7. Apparatus for receiving and conveying box stacks, comprising a pair of carriers, means associating the carriers for alternate vertical travel so that one carrier is positioned to receive a box stack at an upper station while the other carrier is at a lower station, a manual control for governing travel of the carriers, a stack conveyor, means operable to shift the box stack transversely from the carrier at said lower station, a movable transfer means for taking the stack discharged from the carrier and depositing it onto said conveyor, and means for preventing a successive operation of the manual control conditioned by movement

of the stack from the carrier to the transfer means and released by movement of the stack leaving the transfer means.

8. An apparatus for receiving and conveying box stacks, comprising a pair of alternately vertically movable carriers movable between upper and lower stations, hydraulic plunger and cylinder means for each carrier, a passage between said cylinders for passing fluid displaced from one cylinder to the other, a manual control valve in said passage for controlling movement of said carriers, a power driven stack conveyor at said lower station, power driven means operable to shift the box stack transversely from the carrier onto said conveyor, means normally preventing successive operation of said manual control valve conditioned by movement of the stack from the carrier to the transfer means and releasable by movement of the stack leaving the transfer means, and means at the end of said conveyor 15 engaged by the box stack for shutting off the power upon a stack approaching the end of the conveyor.

9. In an apparatus for conveying a box stack, including a vertically traveling carrier, and a mechanism at the end of travel of said carrier for shifting a box stack transversely of the carrier, said mechanism comprising conveyor rollers

10

mounted on said carrier and adapted to support the box stack, and drive rollers engageable by said conveyor rollers at the end of travel of said carrier for operating said conveyor rollers.
